(57) CLAIM

I claim the ornamental design for a foldable handbag hanger, as shown and described.

DESCRIPTION

FIG. 1 is a perspective view of a new design of a foldable handbag hanger in an unfolded condition;

FIG. 2 is a side elevation view of the handbag hanger in the unfolded condition;

FIG. 3 is a rear view of the handbag hanger in the unfolded condition;

FIG. 4 is a front view of the handbag hanger in the unfolded condition;;

FIG. 5 is a top view of the handbag hanger in the unfolded condition; and,

FIG. 6 is a bottom view of the handbag hanger in the unfolded condition.

The broken lines showing of the elements of the handbag hanger forms no part of the claimed design.
